RALPH W. GLENN, OF PIEDMONT, CALIFORNIA

AUTOGRAPHIC MANIFOLDING REGISTER

Application filed May 24, 1927. Serial No. 193,803.

This invention relates to improvements in autographic manifolding registers and consists of the novel construction and arrangement of the parts.

5 The principal objects of this invention are to produce a device of this character that is comfortable to write upon; that is light and simple in construction; easily manipulated and so arranged that the autographic matter 10 on the record strip reads consecutively from the exposed end of the strip towards the supply roll. Other objects and advantages will appear as this description progresses.

In this specification and the annexed drawings, the invention is illustrated in the form considered to be the best, but I do not wish to be understood as confining it to this form because it may be embodied in other forms, and it is also to be understood that in and by 20 the claims following the description it is desired to cover the invention in whatsoever form it may be embodied.

In the accompanying one sheet of drawings Fig. 1 is a longitudinal section in perspective of a register case constructed in accordance with this invention, with the paper strips and manifolding elements omitted. Fig. 2 is a similar view, not in perspective, with the original supply roll and duplicate 30 record roll installed therein, ready for operation. Fig. 3 is a cross-section taken on the line III—III, Fig. 2. Fig. 4 is a similar view taken on the line IV—IV, Fig. 2.

In detail the construction illustrated in 35 the drawings, referring to Fig. 1, comprises the enclosing casing having the bottom 1, the end 2 and the sides 3—3, preferably formed of a single portion of sheet metal blanked 40 into the proper outline and bent to shape and overlapped and welded or otherwise finished at the various corners to give stability to the structure.

The cover 4 follows the contour of the sides 45 3—3 and is hinged at 5 to the upper edge of the end 2. This cover 4 is provided with the overhanging flanges 6 enclosing the sides 3—3, and with the end flange 7 bent at an angle to extend within the confines of the sides 50 3—3. The sides 3—3 have the extension walls

8—8 of reduced height, terminating flush with the end of the bottom 1.

The upper edges of these walls 8—8 support the writing platen 9 composed of a strip of sheet metal having its lateral edges bent back 55 inwardly upon itself to form the guiding edges 10—10. This platen is held in position by the top frame 11, flanged downwardly at 12—12 to enclose the side walls 8—8 to which it is spot welded or otherwise attached 60 to hold the platen in position, see Fig. 4. The outer end of this frame is bent downward, flush with the bottom 1, beyond which it extends as at 13. The inner end of the frame is curved upwardly at 14 and extends slightly 65 beyond the inner end of the platen 9.

The separator 15 is interposed between the platen 9 and the cover 12 and follows the contour of the top frame at 14, from which it is slightly spaced for reasons that will herein-after appear. The top frame 11 is provided with a rectangular opening exposing the platen 9 beneath. The return roller 16 is journaled on the cross-pin 17 the ends of 70 which are riveted in the side flanges 12—12 of the top and is located slightly beyond the end of the platen 9 and protected by the downward extension 13 of the cover. 75

The original supply reel 18 is mounted on the square spindle 19, having the reduced 80 portions 20 adapted to drop within the slots 21 provided in the ends 22—22 of the transverse plate 23, that is spot welded to the bottom 1, as at the points 24—24. These upright supports 22—22 extend upward adjacent the side walls 3—3 and are slightly bent inward to exert a resilient pressure against the sides of the roll 25 of the original supply strip 26. This resilient friction of the side supports 22 maintains a tension on the roll 25 to prevent its unrolling, except by the efforts of the user. 85

This roll 25 is multiple, that is, the original record strip 26 and the duplicate record 90 strip 27 are rolled thereon and adapted to 95 unreel in unison.

In inserting the strips 26 and 27 through the machine for operation, their alined ends are separated from the roll 25, pushed along the bottom 1 beneath the platen 9, around the 100

return roller 16, over the top of the platen 9 and beneath the top 11. The ends of these sheets are exposed through the opening in the top frame 11, where they may be pushed 5 along by the fingers of the operator over the platen and beneath the edges of the top 11 until they reach the separator 15. The duplicate strip 27 is then passed beneath the separator 15 and the original 26, above it so that 10 further pressure downward against the platen 9 and forward towards the upward flange 14, causes the ends of the strips 26 and 27, separated by the separator 15, to move forward, the end of the strip 27 again passing 15 back into the casing between the sides 3—3 and the end of the original 26 passing upward through the slot between the separator 15 and the flange 14 of the top 11, and out of the casing:

20 The sides 3—3 are provided with aligned "button holes" 28—28 having the reduced slots 29 extending downwardly therefrom. These holes 28 are adapted to pass the head 30 of the square spindle 31 that passes 25 through the squared opening in the reel 32 fitting between the sides 3—3. The spindle 31 is provided with a reduced portion 33—33 adapted to drop into the slots 29—29. The exposed end of the spindle is provided with 30 the knurled handle 34 fixed thereon and exposed beyond one of the side walls 3, whereby the reel 32 may be rotated. This reel is provided with a longitudinal slot 35 into 35 which the end of the duplicate strip 27 is inserted for the purpose of reeling up the strip 27 into the roll 36. The duplicate strip 27 is a blank paper. The under surface of the original strip 26 is coated with a suitable non-smudging transfer substance, which 40 surface lies against the top surface of the strip 27 as they pass over the platen 9, whereby any autographic impression written on the top surface of the original strip 26 is transferred to the top surface of the duplicate strip 27. The operator begins his writing at the upper end of the opening through 45 the top 11, adjacent the separator 15. As he writes downward toward the rolls 16 and fills the exposed area on the platen 9, he 50 presses downward on the original strip against the platen and pushes forward toward the separator 15 simultaneously turning the handle 34 clock-wise, which feeds the strips 26 and 27 forward simultaneously, the 55 duplicate 27 passing onto the reel 36 and the end of the strip 26 passing outwardly from the slot between the separator 15 and the flange 14, see Fig. 2, where it may be grasped by the fingers of the operator and torn off 60 along the edge 37 of the flange 14.

I have provided the retainers 38, pivoted at 39 to the side walls 3—3 and provided with the slots 40 adapted to engage above the reduced portions 33—33 of the spindle. 65 For convenience in throwing these retainers

upward in inserting the spindle, I have provided the inturned lugs 41 which may be grasped by the fingers of the operator, to swing the retainers on their pivots 39.

This invention is designed particularly for shop memoranda, phone messages, sketches and other more or less temporary matter of which it may be desirable to preserve a permanent record. The advantage of having such memoranda impressed consecutively 70 from the end of the strip 26 forward as the matter is autographically impressed is sufficiently obvious. So far as I am aware, all duplicating apparatus of this nature provides for the strip being torn off at the end as at 75 13. It is obvious therefore, that the matter impressed on the strip is not consecutive, which has equally obvious disadvantages. In machines, using printed forms, such as printed order registers, and the like, this disadvantage is not material. A further very marked advantage of this construction is the very low comfortable position of the writing platen 9, close to the desk or table top, so that 80 the full arm of the writer is supported while 85 writing.

The return roller 16 may be dispensed with by curling a transverse bead across the end of the platen 9 as a substitute for the roller 16, if it is desired to use only the one length 90 of paper 26, without the duplicate record 27. But where both are used, friction should be eliminated wherever possible to prevent the strips 26 and 27 slipping, one upon the other, which is the purpose of pressing the fingers 95 downward on the platen when the handle 34 is turned.

Having thus described this invention what I claim and desire to secure by Letters Patent is:

1. An autographic register comprising a 105 casing, a platen disposed in said casing, a cover for said platen, a separator between said cover and platen, and means in said casing to lead a strip of paper under the entire length of said platen and then to reverse the direction of said paper and lead it back over the top of said platen to said separator.

2. An autographic register comprising a 110 casing, a platen disposed in said casing, a cover for said platen, a separator between said cover and platen, means to lead a plurality of strips of paper under the entire length of said platen, means to reverse the direction of said strips to lead them back over 115 the entire top of said platen and said separator leading one of said strips from said casing.

3. An autographic register comprising a 120 casing, a roller in said casing, a platen disposed in said casing, a cover for said platen, means for leading a plurality of strips of paper under the entire length of said platen, means for reversing the direction of said strips of paper and leading them back over 125 130

- the top of said platen, means for leading one of said strips from the casing between said cover and platen and means for winding the other strips upon said roller in said casing.
- 5 4. An autographic register comprising a casing, having raised sides upon one end thereof and substantially lower sides upon the other end, a platen mounted in said last mentioned end of the casing, a cover pivoted to the casing covering the raised side portions of said casing, rollers mounted in said raised side portions, means for locking said rollers in said raised side portions, an apertured cover disposed over said platen and secured to said lower side portions of the casing and a separator disposed between said last mentioned cover and said platen to direct a strip of paper from said rollers outside of the casing.
- 10 5. An autographic register comprising a casing, having sides with raised portions at one end and lower portions at the other end, a cover hinged to the back of said casing covering the raised side portions of said casing, a platen disposed in the lower side portion of said casing, an apertured cover extending over said lower side portions of said casing, a separator disposed between said last mentioned cover and said platen, means
- 15 20 in the raised portion of said casing for supporting a supply roller, means also in said raised portion for supporting a record roller and means disposed at the end of said platen for directing the paper from the supply roller
- 25 30 35 under the entire length of the platen and then over the platen towards the record roller.

In testimony whereof I have hereunto affixed my signature.

RALPH W. GLENN.
